UNITED STATES PATENT OFFICE.

FREDERICK U. ADAMS, OF HASTINGS-UPON-HUDSON, NEW YORK.

ROAD-BED AND LEVELER.

1,136,916.

Specification of Letters Patent. Patented Apr. 27, 1915.

Application filed February 7, 1914, Serial No. 817,092. Renewed March 25, 1915. Serial No. 17,049.

To all whom it may concern:

Be it known that I, FREDERICK U. ADAMS, a citizen of the United States, residing in Hastings-upon-Hudson, in the county of 5 Westchester and State of New York, have invented certain new and useful Improvements in Road-Beds and Levelers, of which the following is a specification.

My invention constitutes an improved re- 10 inforced concrete railroad bed characterized by a longitudinal system of construction, uniform and reliable support for the rails and their easy lining-up, repair and replacement, ample bearing on the earth, and safety 15 from heaving and excessive strains.

In the drawings, Figure 1 is a small- 20 scale plan of two bays of single track sub- structure and Fig. 2 a transverse section thereof. Fig. 3 is a large scale plan of part 25 of a bay, Fig. 4 a corresponding transverse section and Fig. 5 a fragmentary side view. Fig. 6 is a small-scale plan of two bays of double track sub-structure and Fig. 7 a corresponding section. Figs. 8 and 9 illustrate 30 a variant in which the rails and ties are borne by leveling devices; Fig. 8 being an side view, partly in section on the line 8—8 of Fig. 9 and Fig. 9 a section on the staggered planes indicated by the lines 9—9 and 35 9^a—9^a, of Fig. 8.

In general terms my invention consti- 40 tutes a permanent substructure of reinforced concrete, extended below frost, and comprising longitudinal or sleeper walls con- 45 tinuously supporting the rails and tied at suitable intervals by transverse walls which extend outwardly in buttresses and increase the transverse stability; anchor bolts set in the concrete for the rail system; and gravel 50 or other ballast filling the cells; and a rail system comprising sleeper, gage and tie plates and rail clamps, all suitably united, bolted except where bolts are unfit for the duty.

In the drawings 1, 1, are longitudinal or 55 sleeper walls directly supporting the rails and tied at suitable intervals by cross-walls 2, in line with which are buttresses, 21, which spread the base and increase the lateral stability. The walls are illustrated as 60 having the conventional batter; but they might have plumb faces. Anchor bolts 1^a are bedded in the walls in proper locations 65 and sets, for the rails; as are steel reinforce-

ments *r*. The cells are filled with tamped 55 ballast B.

In the variant illustrated in Figs. 1 to 7 inclusive, the rail base comprises sleeper plates 3 suitably bedded on the walls 1; and gage-and-tie plates 4, alined thereon by suitable liners 4^a interposed between their down-bent ends 41 and the walls, and contain slots 42 for the bolts 1^b which bind said ends. T-rails 5 are clamped to the tie plates 4 and substructure by clamps 6, slotted for and secured by the anchor bolts 1^a and their nuts and whose clamping ends may extend across the rail tread to and constitute buttresses, 61, bearing against and supporting the web 65 of the rail.

The double track road bed, Figs. 6 and 7, is like the single track save that the cross walls 2 unite the tracks; and the large 70 cells between the tracks are not ballasted.

In the variant illustrated in Figs. 8 and 75 9, I interpose between the substructure and the rail system, levelers 7 adapted to be manipulated to quickly rectify defects in the tread-height of the rails. Said levelers are preferably screw jacks of a suitable type. I 80 illustrate vertically acting jacks comprising nuts 70, formed with sockets 71 for sleeper plates 3; coacting therewith and abutting on base plates 19, set in the wall, and centered 85 thereon by the engagement of a stem and sockets, screws 72 provided with jam-nuts 74 and suitable heads 73, to which spanners or wrenches can be applied to operate the jacks.

For convenience, recesses 18 are formed 90 in the sleeper walls for the jacks.

In the variant the rail system is substantially such as hereinbefore described save that the down-turned ends 41 of the ties 4 are each laterally secured by two bolts 1^b 95 to plates 40^a which extend across the recesses 18; and the rail system is held clear of the substructure by the levelers 7.

I claim:

1. A road bed comprising a reinforced 100 concrete substructure and borne thereby a metal superstructure; said substructure comprising sleeper walls and rail-bolts fixed therein, and cross walls and buttresses in line therewith; and said superstructure comprising sleeper plates, cross ties formed with down-turned ends and bolt-slots, T-rails, 105 rail-clamps formed with rail-web-buttressing

extensions and bolt-slots and serving to adjustably bolt said rails to said tie plates and substructure by means of nuts engaging said rail-bolts; cheek plates between the 5 down-turned tie ends and the sleeper walls, and cheek bolts bolting and laterally confining the last named parts.

2. In combination, a road-bed comprising a reinforced concrete substructure and a superstructure; said substructure comprising 10 sleeper walls and rail-bolts fixed therein; said superstructure comprising sleeper-plates, cross-ties, T-rails, and rail clamps; and adjustable levelers interposed between

said substructure and said ties and rails, and 15 means to secure the ties and rails to the levelers and to the substructure.

3. A road bed comprising a reinforced concrete substructure; a metal superstructure comprising metal cross ties and T-rails; 20 and screw-jacks interposed between said substructure and said ties and rails; and means to secure the ties and rails to the jacks and to the substructure.

FREDERICK U. ADAMS.
